UNITED STATES PATENT OFFICE.

ADAM B. FAHNESTOCK, OF MANHASSET, NEW YORK, ASSIGNOR, BY MESNE ASSIGNMENTS, TO LOCOMOTIVE STOKER COMPANY, OF PITTSBURGH, PENNSYLVANIA, A CORPORATION OF PENNSYLVANIA.

MECHANICAL STOKER.

Application filed September 21, 1923. Serial No. 684,132.

My invention relates to appliances for mechanically, conveying fuel from a supply receptacle to the firing opening of a locomotive or other steam boiler furnace, and is an improvement upon that for which Letters Patent of the United States No. 1,381,977, were granted and issued to Elvin Mechanical Stoker Company, as assignee of Albert G. Elvin and myself, under date of June 21, 10 1921.

The object of my present invention is to provide improved means for feeding fuel, at a desired rate, to a crushing mechanism, reducing it to proper size for firing, and 15 delivering it, in such condition, to the device by which it is projected into the boiler furnace. A further object of my invention is to so dispose the mechanism as to require a minimum of space for its installation, to 20 ensure safety to the operator, and to render it immediately accessible for the removal of any obstructions that, through either accident or design, may have been caused to enter it.

25 The improvement claimed is hereinafter fully set forth.

In the accompanying drawings: Figure 1 is a vertical longitudinal central section through the adjoining portions of a coupled locomotive and tender, illustrating an application of my invention; Fig. 2, a front view, in elevation, of an appliance embodying my invention; Fig. 3, a right hand side view, in elevation, of the same; Fig. 3^a, a vertical longitudinal section through the rear portion of the conveyor casing and adjacent members; Fig. 4, a plan or top view; Fig. 5, a vertical transverse section through the feeder trough, on the line 5, 5 of Fig. 3; Fig. 6, a vertical longitudinal section, through the same, on the line 6, 6 of Fig. 4; Fig. 7, a partial left hand side view; Fig. 8, a vertical section, on an enlarged scale, through the stationary crusher member, on the line 8, 8 of Fig. 4; and, Fig. 9, a similar section, through the movable crusher member, on the same line.

In the practice of my invention, referring descriptively to the specific embodiment thereof which is herein exemplified, it is applied in connection with a tender, indicated, as a whole, by A, and having a coal bin or receptacle, a, and with a locomotive, in-

dicated, as a whole, by B, to which the tender is coupled, in the ordinary manner, by 55 draw bars, C. The firebox, b, of the boiler of the locomotive, is supplied with fuel from the coal bin of the tender, by a feeding and crushing mechanism the construction and manner of operation of which, so far as is 60 necessary to explain my invention, are as follows:

Fuel is transferred from the coal bin, a, of the tender, to a conveyor leading to the stoking appliance on the locomotive, by one 65 or more endless drag chains running on sprocket wheels 4, 4^a, the upper run of the chain extending from the rear to the forward end of the bottom of the bin. This mechanism delivers the fuel to an opening 70 in the bottom of the bin, through which it passes to the stoker conveyor. As herein-after described, there is, in the disclosed embodiment of the invention, a fuel crusher located in the delivery opening of the bin. 75

The drag chain mechanism is preferably housed within a casing 1 below the bin, and crossing this chamber, or located directly below the upper run of each chain, is a plate 1^a which supports the fuel which is 80 being directly acted upon by the chain. The sprocket wheels, 4, at the forward end of the system of chains, are fixed on, and rotate with, a shaft, 40, journalled in the frame 1^a, and the sprocket wheels, 4^a, at the rear end, 85 are fitted to rotate freely, and independently, on a fixed shaft, 41. The chains, 2, are maintained truly in line, in their traverse through the feeder trough, by guide bars, 3, which are approximately equal in depth to 90 the links of the chains, and are interposed between them, as well as located on each side of the set of chains. These bars also serve to support, in part, the mass of fuel, permitting the chains to move more freely. 95

While they are not of the essence of the invention in its broader aspects, they add materially to its efficiency. The links of the chains are, at intervals in the length thereof, provided with upwardly projecting dogs, 100 2^a, which bear against the fuel that is deposited on the chains and promote its forward movement by them.

Intermittent movement, of variable extent, is imparted to the chains, 2, their upper 105 lengths traversing forwardly, i. e., towards

the locomotive, by a motor, 5, located on the locomotive, and rotating a rearwardly extending shaft 6, which is connected, by a universal joint, to a driving shaft, 7. The shaft, 7, carries, at one of its ends, a bevel pinion, 8, engaging a similar pinion, 9, fixed on a shaft, 9^a, which extends transversely to, and below the feeder trough, 1, and is journalled in the supporting frame, 1^a, of said trough. A spur pinion, 10, fixed on the opposite end of the shaft, 9^a, engages a corresponding gear, 11 on a shaft 12, journalled in the frame, 1^a, parallel with the shaft, 9^a, and having an eccentric, 13, secured on one of its ends. A vibratable ratchet casing, 14, on which a plurality of spring pawls, 14^a, ordinarily four in number, are pivoted, is journalled in the supporting frame, 1^a, of 40, on which the sprocket wheels, 4, of the forward ends of the drag chains, 2, are fixed. A curved arm, 14^b, projects forwardly from the periphery of the ratchet casing.

Two parallel swing links, 15, are pivoted to the ratchet casing, said links having a roller, 16, which bears on the eccentric, 13, journalled in their lower ends. The links are of such angular relation to the shafts, 40 and 9^a, that the roller, 16, will be maintained in contact with the eccentric, by its gravity and that of the links, and the latter are maintained in proper position, relatively to said shafts, by a link, 15^a, by which they are coupled to the frame. A ratchet wheel, 17, is fixed on the shaft, 40, and the pawls, 14^a, are, in number and disposition, such that one or another of them is, at all times, in engagement with the teeth of the ratchet wheel. The rotation of the eccentric, 13, as transmitted to the shaft, 40, through the roller, 16, links, 15, ratchet casing, 14, and ratchet wheel, 17, imparts intermittent rotatory movement to the shaft, 40, which, through the sprocket wheels, 4, effects a corresponding intermittent forward traverse of the upper lengths of the drag chains, 2, by which the coal is moved from the coal bin of the tender to the conveyor which delivers it to the stoking appliance on the locomotive.

In order to vary the quantity of fuel delivered by the drag chains, as from time to time desired, the extent of the intermittent forward movements of their upper lengths is correspondingly varied by a regulating mechanism of substantially the following construction. A stop bar, 18, is fitted to slide in a guide, 18^a, which is secured to the frame, 1^a, adjacent to, and in the vertical plane of, the ratchet casing, 14. The stop bar is connected, by a link, 19, to a crank arm, 20^a, on the lower end of a manually operable regulating shaft, 20, which is journalled on the frame, and carries, on its upper end, a handle, 20^b, and latch, 20^c, the latter being adapted to engage the teeth of a quadrant, 20^d. The stop bar is movable,

through the connections above described, towards and from the curved arm, 14^b, of the ratchet casing, 14.

When the stop bar is moved to the limit of its traverse to the left, it will stand entirely clear of the curved arm, 14^b, and will not interfere with its free movement and that of the ratchet casing, to which it is connected. When moved to the right, it limits the movement of the ratchet casing to the clearance between its right hand end and the curved arm, which may be substantially zero at the limit of its right hand traverse, as indicated in Fig. 7. It will be seen that by variation of the position of the stop bar, relatively to the curved arm, a greater or less degree of traverse may be imparted to said arm and the connected ratchet casing, and through them to the forward sprockets, 4, and shaft, 40, varying from the full travel imparted by the eccentric, 13, to zero.

In the operation of stoker fired locomotives, it is frequently necessary to supply them with run of mine coal, which contains lumps that are too large for proper combustion in the firebox, and it is manifestly desirable that they should be capable of using coal of such character, when desired. To this end, a coal crushing mechanism, of substantially the following construction, is preferably provided.

A stationary crusher member, indicated, as a whole, as 21, is secured to the frame, 1^a, below and slightly in advance of the forward ends of the drag chains, 2, and of the coal gates, α' , of the tender. The stationary crusher member is a substantial casting, comprising a plurality of vertical ribs, 21^a, facing towards a movable crusher member, and connected by upper transverse ribs, 21^b, and lower transverse ribs, 21^c. The shaft, 40, which carries the sprocket wheels at the forward extremities of the drag chains, passes through openings, 21^d, in the side walls and ribs of the stationary crusher member, and the chains pass through slots, 21^e, of approximately the same width as the chains, in the top of the stationary crusher member. The openings at the front of the stationary member, at the rear of the upper transverse ribs, 21^b, and between the vertical ribs, 21^a, permit such particles of coal as are so small as not to require crushing, to drop into the conveyor casing, 24^a, without being crushed. The delivery of the coal to the conveyor casing, 24^a, is promoted by inclined deflecting plates, 21^f.

A movable crusher member, 22, of sectoral form is fixed on a shaft, 23, which is journalled in the supporting frame, 1^a, adjacent to its front end, said member having a plurality of sets of teeth, 22^a, which project rearwardly from its curved body, the sets being disposed in parallel vertical planes, and the outer ends of the teeth in curves ec-

centric to the axial line of the shaft, 23. Rocking movement, about said axial line, is imparted to the movable crusher member by a connecting rod, 25, coupled, at one end, to a crank arm, 12^a, on the eccentric shaft, 12, and, at the other, to a crank arm, 23^a, on the shaft, 23.

The shaft, 41, on which the sprocket wheels, 4^a, at the rear extremities of the drag chains, are mounted, is adjustable, in the direction of the length of the appliance, by being fitted in slack adjuster blocks, 26, supported in casings, 26^a, secured to the feeder trough. Any abnormal slack in the drag chains, may be taken up by substituting larger blocks, or inserting shims in the casings. The drag chains are maintained in straight longitudinal direction in the trough, by the guide bars, 3, which practically divide the trough, longitudinally, into a plurality of channels. The guide bars are approximately equal in height to the chain links, and tend to prevent lateral movement of the chains that might be occasioned by large lumps of coal or other material. In order to prevent backward movement of the shaft, 40, which might result by reason of friction from the ratchet casing, pivoted arms, 27, are caused to grip the shaft, by springs, 27^a, and act as a brake to effectually prevent retrograde movement of the shaft.

The screw conveyor, 24, by which the fuel, after passing the crushing mechanism, is carried to the shovels, 26, by which it is projected into the firebox, rotates in a casing, 24^a, extending forwardly and upwardly, from a receiving hopper, 24^b, at its rear end, to the shovel box. Rotation is imparted to the screw conveyor from the shaft, 9^a, through a bevel pinion, 9^b, on said shaft, which pinion meshes with a corresponding gear, 27^a on a shaft, 27, journaled in rear of the conveyor casing, and carrying a universal joint jaw, 27^b. A block, 27^c, journaled in the jaw, 27^b, is coupled, at a right angle to its journals, to a jaw, 27^d, on the forward end of which there is formed a square box, 27^e. A square block, 27^f, having rounded exterior surfaces, is secured upon a short shaft, 24^c, connected to the rear end of the shaft of the screw conveyor.

The rear end of the conveyor casing, 24^a, and the connected receiving hopper, 24^b, are supported on two shoes, 28, which are closed together around a stationary center pin, 29, fitting in a spherical faced bearing in the shoes, 28, said pin constituting a pivot for the entire conveyor mechanism and hopper. The center of the square block, 27^f, is located directly over the axis of the pin, 29, so that, when the front end of the conveyor casing is moved from side to side, in the passage of the locomotive around curves, etc., no movement is imparted to the center of the block. By reason of the fixed relation of the center

of the block, and the center pin, 29, a universal joint is provided, in which there is but a very slight longitudinal movement of the block, in the box, 27^e, due to the raising and lowering of the front end of the conveyor 70 casing, and the lateral movement is so inconsiderable as not to effect any objectionable result in practice.

In the operation of the mechanism described, the continuous delivery of coal from the coal bin on the tender to the conveyor by which it is carried to the stoking mechanism on the locomotive, is effected by the forward movements of the upper lengths of the drag chains, the quantity of coal delivered, being 80 proportionate to the variation of extent of their intermittent movements, which is made, as from time to time desired, by the operator. The larger lumps of coal are crushed in passing between the stationary and movable crushing members, and together with the smaller particles, drop into the receiving hopper of the conveyor casing, and are carried, by the screw conveyor, to the stoking appliance proper. Owing to the comparatively low rate of speed at which the drag chains are ordinarily operated, the safety of the operator is not imperilled, and a cover being placed over the crushing mechanism, there is no liability for him to be injured 90 by it.

I claim as my invention and desire to secure by Letters Patent:

1. In a mechanical stoker, the combination of a fuel receptacle, having a delivery opening; a feed trough, located below said opening; an endless fuel feeding drag chain, adapted to traverse in said trough, below said opening; means for imparting intermittent movement of the upper length of said drag chain, away from the opening of the fuel receptacle; and a conveyor, receiving fuel from the forward extremity of the drag chain and transferring it to a point of delivery.

2. In a mechanical stoker, the combination of a fuel receptacle, having a delivery opening; a feed trough, located below said opening; an endless fuel feeding drag chain, adapted to traverse in said trough, below said opening; upstanding pusher dogs, connected, at intervals, to links of the drag chain; means for imparting movement of the upper length of said chain, away from the opening of the fuel receptacle; and a conveyor, receiving fuel from the forward extremity of the drag chain and transferring it to a point of delivery.

3. In a mechanical stoker, the combination of a fuel receptacle, having a delivery opening; a feed trough, located below said opening; a plurality of endless fuel feeding drag chains, adapted to traverse in said trough, below said opening; a plurality of fixed guide bars, interposed between the 130

drag chain; means for imparting movement of the upper lengths of the drag chains, away from the opening of the fuel receptacle; and a conveyor, receiving fuel from the forward extremity of the drag chain system and transferring it to a point of delivery.

4. In a mechanical stoker, the combination of a fuel receptacle, having a delivery opening; a feed trough, located below said opening; a plurality of endless fuel feeding drag chains, adapted to traverse in said trough, below said opening; sprocket wheels, engaging said chains, at their extremity nearer the fuel receptacle; a shaft, on which said sprocket wheels are mounted; sprocket wheels engaging the drag chains, at the extremity of their system further from the fuel receptacle; a rotatable shaft, on which said last specified sprocket wheels are fixed; means for imparting rotatory movement to said shaft; and a conveyor, receiving fuel from the forward extremity of the drag chain system and transferring it to a point of delivery.

5. In a mechanical stoker, the combination of a fuel receptacle, having a delivery opening; a feed trough, located below said opening; a plurality of endless fuel feeding drag chains, adapted to traverse in said trough, below said opening; sprocket wheels, engaging said chains, at the extremity of their system nearer the fuel receptacle; a shaft, on which said sprocket wheels are mounted; slack adjuster blocks, in which said shaft is journaled; sprocket wheels, engaging the drag chains, at the extremity of their system further from the fuel receptacle; a rotatable shaft, on which said sprocket wheels are fixed; means for imparting rotatory movement to said shaft; and a conveyor, receiving fuel from the forward extremity of the drag chain system and transferring it to a point of delivery.

45 6. In a mechanical stoker, the combination of a fuel receptacle, having a delivery opening; a feed trough, located below said opening; a plurality of endless fuel feeding drag chains, adapted to traverse in said trough, below said opening; sprocket wheels, engaging said chains, at the extremity of their system nearer the fuel receptacle; a shaft, on which said sprocket wheels are mounted; sprocket wheels, engaging the drag chains, at the extremity of their system, further from the fuel receptacle; a rotatable shaft, on which said last specified sprocket wheels are fixed; means for imparting intermittent rotatory movement to said shaft; means for varying the turning movements of said shaft; and a conveyor, receiving fuel from the forward extremity of the drag chain system and transferring it to a point of delivery.

65 7. In a mechanical stoker, the combina-

tion of a fuel receptacle; having a delivery opening; a feed trough located below said opening; a plurality of endless fuel feeding drag chains, adapted to traverse in said trough, below said opening; sprocket wheels, 70 engaging said chains, at the extremity of their system nearer the fuel receptacle; a shaft, on which said sprocket wheels are mounted; sprocket wheels, engaging the drag chains, at the extremity of their system further from the fuel receptacle; a rotatable shaft, on which said last specified sprockets are fixed; a ratchet wheel, secured on said shaft; a ratchet casing, fitting freely on said shaft; spring pawls, pivoted on said casing 80 and adapted to engage the teeth of the ratchet wheel; means for rotating the ratchet casing; means for varying the degree of rotation of said casing; relatively to the shaft; and a conveyor, receiving fuel from 85 the forward extremity of the drag chain system and transferring it to a point of delivery.

8. In a mechanical stoker, the combination of an endless fuel feeding drag chain; means for imparting movement to said chain; a conveyor casing, located in position to receive fuel supplied by the drag chain; a fixed support; shoes, secured to said conveyor, through which it bears on said support; a pivot pin on said support; fitting in spherically recessed bearings in the shoes; a shaft journaled in the casing and carrying the conveyor; a driving shaft, journaled on the fixed support; a connecting member, having a squared recess; a universal joint, coupling said member to the driving shaft; and a curved faced block, secured to the conveyor shaft, and fitting in the recess of the connecting member.

9. In a mechanical stoker, in combination, a fuel bin having a delivery opening, and a trough at its bottom leading to the opening, an endless drag chain the upper run thereof occupying the trough, a conveyor for receiving fuel from the opening and transferring it from the point of delivery to the furnace, and means for imparting intermittent movement to the chain in timed relation with the conveyor.

10. In combination, a fuel bin having a delivery opening and a plurality of troughs at its bottom leading to the opening, endless drag chains the upper run of each occupying one of the troughs, a conveyor for receiving fuel from the opening and transferring it to a point of delivery, and means for imparting an intermittent movement to the chains in timed relation with the conveyor.

11. In a mechanical stoker, in combination, a fuel bin, a conveyor receiving from the bin, and a drag chain movable within the bin for advancing fuel to the place of discharge therefrom into the conveyor, and means for imparting to the chain an inter-

mittent movement in timed relation with the movement of the conveyor.

12. In a mechanical stoker, in combination, a fuel bin, a conveyor receiving from the bin, and a plurality of drag chains movable within the bin for advancing fuel to the place of discharge therefrom into the conveyor, and means for imparting to the chains an intermittent movement in timed relation with the movement of the conveyor.

13. In a stoker for furnaces, in combination, means for delivering fuel to the furnace, a fuel bin having an opening in its bottom, and means for transferring fuel from the bin to the delivering means comprising a plurality of endless drag chains the upper turns of which cross the bin opening, means for advancing the chains to transfer fuel from the bin to the delivery means, and means for varying the movement of the chains independently of the action of the delivering means.

14. In a stoker for furnaces, in combination, means for delivering fuel to the fur-

nace, a fuel bin having an opening in its bottom, and means for transferring fuel from the bin to the delivering means comprising a plurality of endless drag chains the upper turns of which cross the bin opening, means for intermittently advancing the chains to transfer fuel from the bin to the delivering means, and means for varying the movement of the chains independently of the action of the delivering means.

15. In a stoker for furnaces, in combination, means for delivering fuel to the furnace, a fuel bin having an opening in its bottom, and means for transferring fuel from the bin to the delivering means comprising a plurality of endless drag chains the upper turns of which cross the bin opening, means for advancing the chains with a step by step movement to transfer fuel from the bin to the delivering means, and means for varying the length of the steps independently of the action of the delivering means.

ADAM B. FAHNESTOCK.
